DUMPING BUCKET

Richard Walsh, Mobile, Ala.

Application February 25, 1938, Serial No. 192,651

6 Claims. (Cl. 294—73)

The present invention relates to dumping buckets or tubs, and has for one object to provide a structure which may be constructed of aluminum, or other relatively light material, without sacrificing the size or capacity of the tub and to provide a tub which is relatively light in weight to facilitate handling.

Another object of the invention is to provide a bucket or tub structure wherein the weight 10 is distributed over small areas, and wherein the entire load is supported from a substantially central point so that all parts of the device may be made of light material.

A further object of the invention is to provide a bail for the bucket or tub which, when swing down in either direction, will come to rest on the upper edge portion of the bucket and will not fall to the ground or floor; preventing injury to the workmen incident to the bail striking them, 20 particularly on the legs and feet.

The invention also provides a bail and body structure for the bucket wherein the bail may be relatively light, will not collapse under the weight and wherein the side arms of the bail will 25 not have the tendency to collapse or bend toward each other.

The invention also provides an improved latch mechanism for a door when used on the tub or bucket, and which may be connected to the bail 30 for releasing the door when the bucket body is tilted, or released by hand if desired; to provide an improved trip mechanism to release the bucket body when dumping is desired; to provide a tub structure which may be provided with wheels 35 if desired, or without the door for certain uses, as in the handling of sticky material; and to provide a tub or bucket structure with weight distributing and reinforcing straps which are connected to the ends of the bail, and at various 40 points between the sides of the bucket to the bail to suspend the bucket not only at its sides from the bail but also from one or more central points to hold the bucket from collapsing under load.

With the foregoing and other objects in view, the invention will be more fully described hereinafter, and will be more particularly pointed out in the claims appended hereto.

In the drawings, wherein like symbols refer to 50 like or corresponding parts throughout the several views:

Figure 1 is a side elevation of a dumping bucket or tub embodying the features of the present invention.

Figure 2 is a detail front elevation of the door

or gate which may be used on the bucket or tub.

Figure 3 is a top plan view of the bucket of this invention, parts being shown in section.

Figure 4 is a transverse section taken through the same substantially on the line 4—4 of Figure 3.

Figure 5 is a longitudinal vertical section taken through the bucket on the line 5—5 of Figure 3, and

Figure 6 is a front elevation of the bucket. 10

Referring to the drawings, the body portion of the bucket or tub is shown at 10 and is preferably made up of aluminum or other relatively light material. The body portion may be given any suitable shape or form to adapt the bucket or tub to the particular work to be performed, and as shown in the present instance is provided with a rigid end wall 11 and is open at its other end. Reinforcing straps 12 may be suitably placed along the bottom of the body portion and are preferably carried up around the curved closed end of the body portion as clearly shown in Figure 5. 20

The upper marginal edge of the body portion is provided with an angle iron reinforcement 13 which extends along the opposite sides of the body portion and across the rear end wall 11 thereof. The bottom of the bucket body preferably extends outwardly beyond the upper edge thereof at the open end while the side walls 30 are beveled to form a scooplke construction at the front of the bucket or tub. 25

The bucket or tub 10 is adapted to be suspended from a single point, such as at the ring or clevis 14. The clevis 14 is secured by a bolt 35 to the upper ends of a pair of plates 16 which are pivotally mounted upon a rod or cross-bar 17 spaced above the body portion 10. This cross-bar 17 is connected at suitably spaced apart points throughout its length with certain portions or areas of the bucket 10 so as to distribute the weight of the bucket along the cross-bar and to thus relieve the bucket from strains tending to collapse or bulge the bucket under pressure of the weight of the material in the bucket. To this 40 end, the bucket or tub body 10 is provided with a second cross-bar or rod 18 which is disposed through the bucket, transversely thereof and at a suitable point preferably between the upper and lower edges of the sides of the bucket. The cross-bar 18 extends at opposite ends through the sides of the bucket and, as shown particularly in Figure 4, a pair of straps 19 are secured at their outer ends to the projecting ends of the cross-bar 18, are carried downwardly against the sides and 45

50

55

55

across the bottom of the bucket 10 to the central portion thereof, from which the straps 19 are turned upwardly within the bucket 10, and are secured at their inner ends to the intermediate portion of the rod or bar 18. Each strap 19 thus provides an independent hanger which embraces a side portion of the bucket so that the side portions of the bucket are independently suspended from the cross-bar 18. Pressure of material in 10 the bucket, tending to bulge the bottom thereof downwardly is offset by the upturned inner ends of the straps 19.

The cross-bar 18 is suspended from the upper cross-bar 17 by a pair of outer links 20 which 15 interconnect the outer ends of the cross-bars 17 and 18, and by a pair of inner links 21 which extend between the cross-bars at their intermediate portions. It will be noted that the inner links 21 are disposed adjacent to the clevis 20 plates 16 so that the middle portions of the bars 17 and 18 and of the bottom of the bucket are suspended directly from the clevis 14. The straps 19 with their suspension bars 17 and 18 are disposed at a suitable point intermediate the 25 opposite ends of the bucket or tub so as to obtain the desired balance of the tub for carrying the material and also for dumping the same. To hold the bucket from swinging backwardly on the links 20 and 21, a chain 22 may be connected 30 at one end to the clevis bolt 15 and at its other end to the rear wall 11 of the bucket so that when the bucket is in horizontal position, as shown in Figure 5, the chain 22 is taut and the bucket is held from swinging backwardly.

35 For releasably holding the bucket from swinging downwardly and forwardly when in carrying position, a suitable trip is employed, and as shown comprises a cross-rod 23, secured between the forward ends of the reinforcing angle bar 40 13, and on which is pivoted at an intermediate point, a pair of short links 24 spaced apart a short distance and carrying between their free ends a spacer or crosspiece 26 adapted to engage in the bill of a hook 27 pivotally mounted upon 45 a bolt 28 carried between a pair of adjustable links 29 which are pivoted to the upper cross-bar 17. The hook 27 is provided with a shank 30 to which may be attached a chain 31 or other suitable operating device by means of 50 which the hook 27 may be swung upon its pivot 28 to disengage the hook 27 from the spacer 26 and thus trip or release the lower pair of links 24 from the upper pair of adjustable links 29. The released position of the trip is shown in 55 Figure 1. When the trip is released the bucket may be swung forwardly and downwardly as shown.

The forward end of the bucket or tub may 60 be reinforced in a manner similar to the intermediate portion thereof. In this instance the front cross-rod 23 extends through the sides of the bucket and carries the outer ends of straps 32 which are carried down against the outer sides of the bucket across the bottom thereof to 65 a middle point, as shown in Figure 5, and thence are turned upwardly a short distance and are engaged upon a bottom cross-rod 33 which serves to distribute the weight imposed on the bottom of the bucket along the rod to the sides thereof.

70 The upper portion of the bucket is provided with a pair of aprons 34 which extend a short distance backwardly along the sides of the bucket and extend across the front thereof to 75 a considerable extent so as to direct and cen-

tralize the material of the bucket as it is being poured from the open end thereof.

A plurality of agitator or spreader bars 35 are secured to the bottom of the bucket adjacent its forward end and are inclined upwardly 5 and backwardly so that the material in the bucket, tending to pack or jam the mouth of the bucket, will be broken up and the particles thereof be caused to flow freely about and between the bars 35 during the pouring operation, 10 and the bars 35 will also insure that the material flows evenly during the dumping action.

While the invention may be used with various types of buckets or tubs, with or without doors, the present embodiment shows the invention as 15 applied to a bucket or tub having a door or gate 36. This door or gate 36 is shown in detail in Figure 2 and may be constructed of an aluminum body or plate rolled over its upper end to provide a hinge sleeve 37 fitting upon the rod 20 23 serving as a pivot for the door, the door extending downwardly and forwardly from the rod 23 and adapted to close against the upper surface of the bottom of the bucket 10. The door 36 may have a plurality of vertical reinforcing straps 38 to stiffen the door, and may be further reinforced by angle irons 39 extending along the lateral and free marginal edge portions of the door, the angle irons 39 being spaced apart at the central portion of the door 25 to admit free operation of a latch bolt 40 which is slidably mounted in bearings 41 secured to the outer surface of the door. The bolt 40 is adapted to drop down into a suitable keeper socket 42, shown in Figure 6, for locking the 30 door closed. The latch bolt 40 is disposed vertically on the door and is provided with a head at its upper end beneath which one leg of a latch lever 43 engages, the latter mounted at its upper end on a pivot 44 projecting from the 40 door 36. A stop 45 is also disposed upon the outer face of the door to hold the latch lever in releasing position, as shown in Figure 6. A latch cord 46 is adjustably secured between the free 45 end of the latch lever 43 and the cross-rod 17 so that when the bucket is tripped and swings downwardly at its forward end the latch cord 46 is drawn taut and swings the latch lever 43 into the position shown in Figure 2, engaging the head of the bolt 40 and sliding the same upwardly to free the door. The weight of the material plus the taut latch cord 46 swings the door 36 into open position, as shown in Figure 1, so that the material of granular or liquid consistency may pour from the open end of the 50 bucket.

The bucket body 10 is thus suspended from a bail 17 having a plurality of transversely spaced apart arms 20 and 21 which are pivotally connected by the rod 18 to the upper ends of the 60 U-shape straps 19. This structure independently suspends the portions of the bucket body 10 which are included in the respective straps 19 so that each portion or section of the bucket body 10 is independently supported and reinforced and 65 hangs from the bail without transmitting any appreciable pressure to the adjacent portions of the bucket body. This prevents the collapse and the bulging of the bucket body under load, and the bucket body may be made relatively large as 70 compared with its weight and thickness and strength of the material or materials of which the bucket body is constructed.

This sectional suspension and reinforcement of the bucket body is had at its open end by use of 75

the straps 32 which are connected to the front rod 23, the latter in turn being releasably connected to the bail by the trip hook 27 so that the pressure in the front end of the bucket does not tend to collapse the mouth of the bucket. The straps 32 and 19 are disposed in endwise relation across the bottom of the bucket and thus divide the same into transversely reinforced and independently suspended zones or sections.

10 The bail 17 and its arms 20 and 21 are so proportioned, or are of such length that the bail when released at its upper end will swing down and strike against and be supported on the upper edge of the bucket. The angle iron reinforcement 15 13 at the top of the bucket will take up shock and wear and prevent the bail from swinging down and striking the feet and legs of workmen handling the bucket.

10 The hook 27 and the adjustable links 29 have 20 series of holes therein for admitting adjustment to accommodate the trip to conditions of use. The hook 27 has its bill extending forwardly and upwardly so that the chains 31 may be pulled from in front of the bucket to release the trip 25 and swing the front end of the bucket downwardly.

While one particular form or construction of bucket 10 has been illustrated and described for the purpose of setting forth this invention, it is 30 to be understood that the invention may be applied to buckets of various types now used and known in the art.

In use, the bucket or tub is used with or without the door 36, and in any event is supported 35 from a single point upon the hoist rope or chain from the clevis 14. The clevis 14 is connected to the bail by the plates 16 and the bail is provided with the links or arms which swing about the cross-bar 18 so as to pivotally support the bucket. The trip holds the bucket from tilting 40 forwardly while the anchor chain 22 holds the bucket from tilting backwardly. The material is placed in the bucket in the usual manner and the bucket thus held against swinging, as shown 45 in Figure 5, is elevated or lowered into the dumping location. The chain 31 is now pulled and causes the trip hook 27 to move downwardly and inwardly from the spacer 26 of the trip links 24 for freeing the latter whereupon the material in 50 the bucket flows toward the door 36 and the bucket tilts forwardly as shown in Figure 1, at the same time releasing the latch bolt and opening the door. The aprons 34 hold the material from flowing over the forward sides of the bucket 55 and directs the material downwardly and centrally toward the door, the material flowing out about the rods 35 in a continuous and even stream.

It is obvious that various changes and modifications may be made in the details of construction and design of the above specifically described embodiment of this invention without departing from the spirit thereof, such changes and modifications being restricted only by the scope of the 60 following claims:

What is claimed is:

1. A dumping bucket, comprising a bucket body, independent reinforcing straps disposed against the sides and bottom of the bucket body with the inner ends of the straps extending upwardly through the bottom of the bucket body, and a bail having a plurality of transversely spaced apart arms pivotally secured to the ends of the straps for independently suspending the portions of the 65
- 5 bucket body lying within the respective strap from the bail.
2. A dumping bucket, comprising a bucket body, a plurality of U-shape straps engaging in a transverse row across the bottom of the bucket body and extending upwardly against the sides and through the bottom thereof, and a bail having a plurality of transversely spaced apart arms pivotally connected to the upper ends of the straps for independently suspending the sections of the 10 bucket body included within said straps.
3. A dumping bucket, comprising a bucket body, a pair of reinforcing straps extending downwardly from opposite sides of the body and having their inner ends upturned through the bottom of the 15 bucket, a cross-bar extending through the bucket body and engaging said cross-bar at its end and intermediate portions for supporting the opposite side sections of the bucket body independently from said cross-bar, and a bail having transversely spaced apart arms pivotally connected at spaced portions along said cross-bar to independently support the various portions thereof between the ends of said straps.
4. A dumping bucket, comprising a bucket body, 20 reinforcing straps extending downwardly at the outer sides of the body and inwardly across the bottom thereof and having their inner ends upturned through the bottom of the bucket body, transverse rods secured through the bucket body 25 and engaging the upturned ends of said straps for independently supporting the sections of the bucket body included within the straps from the respective rods, and a bail connected to said rods for independently suspending said portions of 30 the bucket body from the bail.
5. A dumping bucket, comprising a bucket body closed at one end and open at its opposite end, pairs of reinforcing straps disposed against the outer sides of the bucket body at an intermediate 35 point and adjacent its open end, said straps extending inwardly beneath the bottom of the bucket body and having their inner ends upturned through the bucket body for dividing the same into lateral sections, transverse rods secured 40 through the bucket body for the intermediate and end straps and engaging the upper ends thereof for supporting the body sections independently from the rods, a bail pivotally connected to the intermediate rod, and a releasable trip disposed 45 between the end rod and said bail for independently supporting the body sections from the bail.
6. A dumping bucket, comprising an aluminum body portion, reinforcements for said body portion for holding the same to shape and including 50 a marginal bar about the upper edge of the bucket body, a plurality of upturned straps disposed endwise in a row beneath the bottom of the bucket body and having their free ends upturned through the bottom of the body and against the sides 55 thereof, a rod mounted transversely through the bucket body and connected to the upper ends of said straps for supporting the bucket body in zones to distribute the internal stresses of the material in the bucket independently to the zones, 60 and a bail having a plurality of transversely spaced apart arms corresponding to the upturned ends of said straps and pivotally connected to said transverse rod adjacent the respective strap ends for directly and independently suspending 65 said zone portions of the bucket body from the bail.

RICHARD WALSH.
